UNITED STATES PATENT OFFICE.

JOHN ENLOE BEOYLES, OF COCO SOLO, CANAL ZONE, ASSIGNOR OF ONE-HALF TO
H. E. ROBERTSON AND T. H. WEILME, BOTH OF RUSSELLVILLE, MISSOURI.

SUPERAIRSHIP.

Application filed July 28, 1925. Serial No. 46,617.

The present invention relates to super airships, and has for its principal object to provide a new sort of lift therefor. Ordinarily the great speed of lighter-than-air ships as constructed at present create a very small aero-dynamical lift in proportion to their size. On the other hand, aeroplanes or heavier-than-air vehicles do not use the sustaining lift of lighter-than-air gases. Neither the lighter-than-air ship, nor the aeroplane, can both rise and descend, vertically from, or to a landing as they are now constructed, and do so satisfactorily. The helicopter can do this, but is not efficient on account of the small factor of safety, and its inability to cruise at great speed after getting into the air.

By using the power plant assemblage as is clearly disclosed in my application bearing Serial No. 21,873, filed April 9, 1925, the full horse power thereof may be utilized as additional sources of lift as well as other features, by the turning of the motor about its horizontal axis into a vertical plane, we see, that this enables lighter-than-air ships to ascend when heavier-than-air, and descend when lighter-than-air in a vertical plane without the use of ballast or the necessity of valving out expensive lighter-than-air gases.

Now supposing we load an air ship to full carrying capacity so that when all horse power of the air ship is used to ascend vertically, we are just able to take off at usual rising speed of lighter-than-air craft. Now

after we have obtained desirable altitude to clear all obstructions in our desired line of flight, if we were to pivot our motors back into the horizontal plane creating a pulling force in a direction of flight desired, our

source of lift created by the propellers pulling vertically is lost so that the air ship would have the same problem of the helicopter, for unless the vertical pull of the propellers is maintained we have no sustaining source of lift to keep us in the air.

Now the present invention overcomes this difficulty. It combines all of the valuable points of an aeroplane with all those good points of lighter-than-air craft, and by a novel arrangement creates both an aero-dynamical, as well as lighter-than-air lift with the minimum of dead weight, securing the maximum of useful carrying capacity with the least amount of head resistance to

forward speeds. This invention consists of the idea of attaching aeroplane wings to the hulls of the conventional rigid lighter-than-air craft so that greater lift can be obtained up to a certain point. As the head resistance determines the number of horse power required for certain speeds, the number of wings attached increases in direct ratio as the head resistance, and horse power required. So it is desirable to have aeroplane wings attached to the number or size which will create aero-dynamical lift equal to that additional source of lift obtained by the total horse power of the airship, driving propellers in vertical plane. After the motors are used for lifting the airship to the desired altitude vertically, and are swivelled back into a horizontal plane for forward propulsion, there is instantly obtained aero-dynamical lift equal to the lift attained by the motors pulling vertically, and as the speed is increased, the lift is also increased up to a maximum efficiency. This aero-dynamical lift is created by the wings the same as on an aeroplane. The attachment of aeroplane wings have other advantages also, such as a help to the maintenance of the air ship's equilibrium, possibility of reaching higher altitudes, elimination of tons of water of ballast, and saves valving of hydrogen or helium for the purpose of landing.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of a super-air ship embodying the features of my invention,

Figure 2 is a front elevation thereof,

Figure 3 is a fragmentary detail plan view showing the pivoted wing structure,

Figure 4 is another detail plan view of one of the wings showing portions in section,

Figure 5 is an edge elevation thereof, showing the hinge in section,

Figure 6 is a fragmentary detail bottom plan view showing a pair of hingedly mounted doors in the bottom of the lower cabinet of the super-air ship,

Figure 7 is a fragmentary enlarged detail longitudinal section taken particularly through the structure shown in Figure 6,

Figure 8 is a detail longitudinal horizontal section through the cabinet showing particularly the base of a lifting member,

Figure 9 is a transverse vertical section through the hull,

Figure 10 is a side elevation of a modification of the super-air ship,

Figure 11 is a front elevation thereof,

Figure 12 is a sectional view through one of the wings thereof,

Figure 13 is a vertical section taken through a portion of one of the wings showing a tube which passes vertically through the wings, and

Figure 14 is a top plan view of the structure shown in Figure 13.

Referring to the drawings in detail and particularly to Figures 1 to 9 inclusive, it will be seen that the letter A designates generally the hull having a cabinet B extending longitudinally therebelow and a cabinet C extending longitudinally thereabove. The construction of the hull is of the well known braced outer wall formation, which is comparatively light, and I brace the same by horizontally extending floors 5, so that the hull in transverse cross section presents an annular formation as is indicated in Figure 9. These floors 5 will be constructed of strong light material, and may be utilized as sleeping quarters as the cabinets on this super-air ship will not be sufficiently large to house the large number of persons who may be carried by the air ship. Elevator shafts 6 extend vertically and diametrically through the hull from the lower compartment B to the upper compartment C in order that persons may reach the upper compartment from the lower compartment and vice versa, and in order that access may be had to the different floor levels in the hull. This whole transverse vertical section of floors between wing assemblies will be of a strong fire-proof construction, so as to aid in the strength of the hull as a whole. The front and rear walls of the bracing floor compartments between the wing assemblies are heat insulated so as to serve as a factor of safety to the lives of passengers in case of fire in the airship. There will also be several floor levels as is indicated at 7 in the lower cabinet B. The roof or top of the upper cabinet C is formed flat, and will provide a landing for aeroplanes. A plurality of gas bags 8 will be attached to the hull A. In the present instance I have shown two of these gas bags 8 extending longitudinally above and one to each side of the hull A, being held in place by suitable members 9 also connected to wing structures 10. These wing structures 10 extending to the sides of the hull, as is clearly shown in Figures 1 and 2, and there may be

any number of these structures and each structure may have as many wings thereto as may be found desirable, necessary, and practical. Each wing of each wing structure includes a fixed section 1 rigidly associated with the hull, and a movable section 12. The fixed section is provided at its ends with vertically spaced parallel apertured ears 13 for receiving the inner reduced end 14 of the movable section 12, and a pivot pin 15 or bolt extends through the ears 13 and reduced end 14, so that the movable section 12 may swing through an arc of ninety degrees so as to be disposed outwardly, that is at right angles to the axis of the hull or parallel thereto, as is indicated in dotted lines in Figure 3. If desired, the sections 12 may be connected by suitable struts 16, so that those movable sections in one wing structure may all swing together. The movable wings of the wing structures on one side of the hull are connected by flexible cables 17 or the like which have their ends fixed to the nose and tail of the hull in any suitable manner as is indicated in Figure 1, so that said movable sections of the wing structures may be held in their active or extended positions, as is indicated in Figure 2. It is evident that by slackening the cables 17 from the nose of the hull A that the movable sections of the wing structures may be folded in longitudinal alignment parallel with the axis of the hull in order that the super-air ship will be able to maneuver into a hangar, or some other relatively restricted space. In the present embodiment of the invention I utilize two sources of propulsion on each wing structure, as is clearly shown in Figure 1 of the drawings at 19. These sources of propulsion are of the construction disclosed in my application bearing Serial No. 21,873, filed April 9, 1925.

The source of power for operating these propelling devices 19, for lighting the super-air ship, for furnishing gas for the lighter-than-air gas bags 8, and conserving fuel has been disclosed in my application relating to power plants, Serial No. 45,663, filed July 23, 1925. If desired, the anchorage assembly for airships may be incorporated in this airship structure as is shown to advantage in my allowed application, bearing Serial No. 6,065, filed January 31, 1925. These three applications mentioned really make this super-air ship possible and practical.

Particular attention is now directed to Figures 6 and 7, taken with Figure 1, wherein it will be seen that caster-like wheels are provided for this super-air ship and as all the wheels are identical in construction, a detailed description of one will suffice for all. A shank 20 terminates at one end in a head 21, and at its other end in a fork 22. A suitable rubber tired wheel 23 is journaled in the extremities of the fork 22

in any suitable manner. A cylinder 24 is provided in the cabinet B for slidably receiving the head 21, which has attached thereto a cable 25 leading to a suitable winch (not shown) for the purpose of lifting the wheel structure when desired. An opening is provided in the bottom of the cabinet B, and has a pair of doors 26 hinged to close the same, as is indicated at 27. The meeting edges of these doors are provided with registering notches 28 to form a square opening when the doors are closed. The shank 20 is square in cross section so as to extend through the opening formed by these notches 28. The doors are held in a closed position by slideable bolts 29 associated with loops 30 on the bottom of the cabinet, and loops 31 on the doors 26. Apertured lugs 32 are provided at the free edges of the doors 26 so that a pin 33 may be inserted therethrough, and through one of the apertures 34 provided in the shank 20. Thus, the doors may be opened, and the wheel structures extended so that when the doors 26 are closed, the wheel will be resting on the ground so as to take up strains which would otherwise have to be borne by the sliding shaft mast, and the bolts 29 may be slid to engage the loops 31 to prevent the doors 26 from opening, and the shank 20 extending through the opening formed by the notches 28 will be prevented from turning and may be locked to the doors further by means of pin 33, lugs 32, and apertures 34, which also determine height of airship from ground and keep wheel from sliding up to doors.

A bracing bracket, as is illustrated in Figure 8, is utilized as a means for taking up strains exerted on the mast 37 when the wind causes the airship to revolve about it. The members 10' are used to brace that part of cabinet B to which the sliding shaft mast 37 is attached. This section of cabinet B is the base of the sliding shaft mast and can be raised to or lowered from the airship vertically and involve the same principles as are disclosed in Patent No. 1,544,431. When the base of the mast is resting on the ground and held thereby such means as is shown in my application bearing Serial No. 6,065, the rest of the airship will as a rule, be lighter than air, and will pivot about the mast 37 as a weather vane, which tells the direction of the wind. When the base of mast 37 is lifted into place in section B, then the bracing bracket is disassembled, and the airship rests on wheels 23 when it is heavier than air. These wheels 23 in connection with the motors enable the airship to be maneuvered into and out of a hangar without the aid of a field crew. The main purpose of these wheels is to take up the strain which would be exerted against the sliding shaft mast caused by the wind

forcing the nose of the airship up and down.

Referring now particularly to the modification shown in Figures 10 to 14 inclusive, it will be seen that I provide a hull A', lower cabinet B', and upper cabinet C', which are identical with the hull A, and cabinets B, and C, respectively, as described above, except as may be hereinafter modified. The wings E are shaped in substantially the same manner as ordinary aeroplane wings, but are constructed hollow as is indicated to advantage in Figure 12, the walls of these hollow wings are reinforced as is indicated at 40 so as to be strong and light. A plurality of tubes 41 extend vertically through the wings E so as to divide the interior of each wing into a plurality of compartments, each compartment adapted to receive a lighter-than-air gas bag 42. Propulsion units 43 are mounted one at the top, and one at the bottom of each tube 41. These propulsion units 43 will be the same as those described in said application Serial No. 21,873. These wings will have the usual lighter-than-air lift features, and also the aero-dynamical lift features, and the structure of the propulsion units 43 will allow them to be used so that they will function as a helicopter in addition to the lighter-than-air lifts for raising the air ship vertically, and they may then be shifted so as to propel the airship forwardly at which time the aero-dynamical lift will be utilized.

As is well known in the art of aeronautics, there is a negative lift at the upper surface 100 of the plane caused by suction, and a positive lift at the bottom of the plane, caused by the crowding of the air. These negative and positive lifts may also be present with my improved wing structures E. By suitable regulation of these negative and positive lifts, the super-air ship may be made to rise or descend as may be desired during its flight without the necessity of valving lighter-than-air gas in the bags 42, and also without the necessity of changing the speed of the propulsion units 43. The structure for taking advantage of the negative and positive lifts just mentioned, is illustrated to advantage in Figures 13 and 14. Referring to this structure in detail it will be seen that at each end of each tube 41, there is provided a pair of hinged valves 45 normally held closed by a suitable spring hinge structure 46. Branches 47 of cable 48 are attached to the valves 45, and pass over a pulley structure 49 and may be terminated at a suitable convenient point in the control cabinet. It will thus be seen that by suitable regulation of these valves 45, the negative and positive lifts may be reduced, since the more the valves are opened, the greater will be the reduction in the lifts. Thus the ascent and descent of the super-air ship may be conveniently and quickly controlled dur-

105

110

115

120

125

130

ing the flight of the airship without interfering with the engines or the lighter-than-air gas bags. It will also be seen that these valves may be utilized for taking the place 5 of ballasts. For instance, if the airship should be leaning to the left because of air currents, the valves on the wings to the right could be opened, thereby decreasing their efficiency because of the decrease in negative 10 and positive lifts, and consequently tending to right the airship. These valves may be opened to advantage when the air ship is moving vertically either in its ascent or descent so as to decrease the resistance of 15 the wing structures.

From the above it will be seen that this invention comprehends all of the above method of strengthening the main frame or hull of air ships so that the new sources of 20 lift obtained either aero-dynamically, or with the use of lighter-than-air gases may be assembled together in a coordinating, efficient, and harmonious new huge super-airship which combines all of the advantages 25 of existing air-crafts as well as new additional advantages recited above. Also, this invention rests on the novel merits of construction, which furnish simple, efficient, and reliable means of control of all parts by 30 means of which the main object of obtaining new and greater lifting capacity of air ships are attained. The present embodiments of the invention have been disclosed merely by way of example, since in actual 35 practice they will attain the features of advantage enumerated as desirable in the statement of the invention and the above description.

It will be apparent, however, that numerous changes in the details of construction, in the sizes, in the materials and in the combination and arrangement of parts may be resorted to without departing from the spirit or scope of the invention as herein- 45 after claimed or sacrificing any of its advantages.

Having thus described the invention, what I claim as new and desire to secure by Letters Patent is:—

50 1. In a super-air ship construction, a hull, aero-dynamic lifting wings on the hull of hollow construction, tubes extending vertically through the wings, and dividing the

wings into compartments, and lighter-than-air gas bags in the compartments.

55

2. In a super-air ship construction, a hull, aero-dynamic lifting wings on the hull of hollow construction, tubes extending vertically through the wings, and dividing the wings into compartments, lighter-than-air 60 gas bags in the compartments, and valve structures at the ends of the tubes for reducing the positive and negative aero-dynamic lifts of the wings.

65

3. In a super-air ship construction, a hull, lift means associated with the hull, a cabinet associated with the hull, the bottom of said cabinet being provided with a plurality of openings, a pair of doors hingedly mounted for association with each opening, the 70 doors of each pair having notches at their free ends, a cylinder in the hull above each opening, a shank associated with each opening and having a head slideable in the cylinder at one end, and a fork at the other end, a wheel journaled in the fork, means whereby the wheel may be extended out of the hull or in the hull, said doors adapted to be engaged in a closed position with one end of the fork for holding the wheel supported 75 outwardly of the hull, means for holding the doors in a closed position.

75

4. In a super-air construction, a hull, lift means associated with the hull, a cabinet associated with the hull, the bottom of said 80 cabinet being provided with a plurality of openings, a pair of doors hingedly mounted for association with each opening, the doors of each pair having notches at their free ends, a cylinder in the hull above each opening, a shank associated with each opening and having a head slideable in the cylinder at one end, and a fork at the other end, a wheel journaled in the fork, means whereby the wheel may be extended out of the hull 85 or in the hull, said doors adapted to be engaged in a closed position with one end of the fork for holding the wheel supported outwardly of the hull, means for holding the doors in a closed position, lugs on the doors 90 provided with apertures, said shanks provided with apertures, and pins insertible through the lugs, and the apertures of the shanks.

90

In testimony whereof I affix my signature.
JOHN ENLOE BROYLES.
